UNITED STATES PATENT OFFICE

SAMUEL J. DANERHIRSCH, OF MONTCLAIR, NEW JERSEY

PICKER WITH LEATHER NOSE

Application filed February 29, 1928. Serial No. 257,844.

My invention relates to improvements in the kind of loom-pickers used in connection with reciprocating picker-sticks; in its development I had the following objects in mind:

1st, to make such a picker, having its body formed in a single piece of homogeneous material and a part connected thereto to receive the shuttle impact having different properties than the body;

2nd, to make the picker as light as possible to over-come the disadvantages of excessive momentum in the reciprocating movement;

3rd, to provide a dulling of the effect of the blow at the point of impact of the shuttle;

4th, to reinforce the dulling material by the solid part of my picker.

I attain these objects by the mechanism illustrated in the accompanying drawings, in which:

Figure 1 shows my picker assembled in parallel perspective.

Figure 2 is a top view of my picker with the nose member thereof removed.

Figure 3 is a top view of the nose member of my picker removed from the picker body.

Similar numerals refer to similar parts thruout the several views of the drawing.

The solid part 4 is cast or molded or otherwise formed in a single piece in a homogeneous mass, either a resinous material, such as bakelite a light casting of metal or any other suitable substance; the shape of this

part is substantially rectangular and in this respect corresponds to the customary form of such pickers, but it is a little shorter in the front where the protruding points 9 are molded or cast substantially as a unit with

this part, and the sides of this part are recessed at 6 to receive the sides of the nose shown in Figure 3.

That nose consists of shell 7 in which are assembled by a suitable adhesive material the

45 inserts 8.

These parts 7 and 8 are assembled with the solid part 4 by any suitable fastening means such as rivets 10, the points 9 serving as additional holding means. The whole assembly forms an enclosure of substantially

rectangular shape from which protrudes lug 5, which serves to extend the bearing surface of one of the shorter sides of the rectangular opening in part 4. In my improvement this lug 5 forms an integral part of the rectangular piece 4, and it is cast or molded or otherwise formed as a unit with the latter.

Pickers, as principally used in the art to-day, are made of an inert, sluggish, material, such as raw-hide, leather and specially prepared, assembled fabrics. Such material is employed in order, first, to absorb the blow of the impact of the shuttle and thus to prevent its destructive effect being transmitted to the mechanism of the loom, and, second, to prevent a rebound of the shuttle, which would be the necessary reaction from the impact, if the shuttle should strike a more resistant material. With such a rebound the mechanism of the loom could not effectively throw back the shuttle on the return motion of the reciprocal stroke. But owing to the disadvantages of the above named inert materials as active parts of machinery,—they gradually yield, warp under exposure to the atmosphere, draw vermin, and under the pounding action their organic structure is "killed" and is subject to rapid deterioration,—I am using them only at the point where necessary, shaping the rest of the picker integrally from a homogeneous material used to greater advantage where the function is essentially that of moving machine-parts.

My improvement being primarily intended as a replacement part, for pickers used now on standard machinery, it does not show novelty in the outline of its form and its new features can readily be incorporated in the design of the various prevailing types. I am able to effect this adaption, because for the picker nose I use an inert material which, though used in a restricted space affords all the shock absorbing qualities necessary in the picker. Choice leather or a multiplicity of layers of a fabric of great tensile strength may be used for the outer strap of the nose; however I have attained the best results with sharp leather which owing to its unique interwoven structure can effectively be used in thin layers for this purpose for my picker.

The inserts may be of carefully graded strips of leather of different degrees of hardness and softness in transverse layers, to form a compact laminated cushioning element between the lug 5 and shell or strap 7 of the picker nose, or I may use an inert slug of non-resilient properties, like raw-hide, lead, etc.

1. A picker, consisting of an integrally formed picker body of molded, homogeneous material, of rectangular, looped formation, with parallel opposite sides having recesses at one end, a lug at said end between and integral with the sides of said body, a slug comprising a plurality of layers of inert material, adjacent said lug and covering said lug and end of said body, an inert strap fitted into said recesses and covering said slug, and means securely fastening said slug and strap in operative relation to the looped body.

2. A picker, consisting of an integrally formed picker body of molded, homogeneous material, of rectangular, looped formation, with parallel opposite sides having recesses at one end, a lug at said end between and integral with the sides of said body, a slug of inert material, adjacent said lug and covering said lug and end of said body, an inert substantially U-shaped nose fitted into said recesses and covering said slug, and means securely fastening said slug and nose in operative relation to the looped body.

3. A picker, consisting of an integrally formed picker body of molded, homogeneous material, of rectangular, looped formation, with parallel opposite sides having recesses at one end, a lug at said end between and integral with the sides of said body, a series of pointed holding members substantially integral with and on said end of said body, a slug comprising a plurality of layers of inert material, adjacent said lug and covering said lug and end of said body, an inert strap fitted into said recesses and covering said slug, and means securely fastening said slug and strap in operative relation to the looped body.

4. A picker, consisting of an integrally formed picker body of molded, homogeneous, resinous material, of rectangular formation, with parallel opposite sides having recesses at one end, a lug at said end between and integral with the sides of said body, a slug comprising a plurality of layers of inert material, adjacent said lug and covering said lug and end of said body, a shark leather strap fitted into said recesses and covering said slug, and means securely fastening said slug and strap in operative relation to the looped body.

5. A picker, consisting of an integrally formed picker body of molded, homogeneous, resinous material, of rectangular formation, with parallel opposite sides having recesses at one end, a lug at said end between and integral with the sides of said body, a slug com-

prising a plurality of layers of inert material, adjacent said lug and covering said lug and end of said body, an inert strap fitted into said recesses and covering said slug, and means securely fastening said slug and strap in operative relation to the looped body.

6. A picker, consisting of an integrally formed picker body of molded, homogeneous, resinous material, of rectangular formation, with parallel opposite sides having recesses at one end, a lug at said end between and integral with the sides of said body, a slug comprising a plurality of layers of inert material, adjacent said lug and covering said lug and end of said body, an inert leather strap fitted into said recesses and covering said slug, and means securely fastening said slug and strap in operative relation to the looped body.

Signed at New York, in the county of New York and State of New York, this 24th day of February, A. D. 1928.
